Primary Examiner — Joseph Kukella*Assistant Examiner* — Heather Wencl(74) *Attorney, Agent, or Firm* — Troutman Pepper Locke LLP(57) **CLAIM**

The ornamental design for an occupancy sensor, as shown and described.

DESCRIPTION

FIG. 1 is a front-top perspective view of an occupancy sensor.

FIG. 2 is a back-bottom perspective view of an occupancy sensor.

FIG. 3 is a front-side view of an occupancy sensor.

FIG. 4 is a back-side view of an occupancy sensor.

FIG. 5 is a left-side view of an occupancy sensor.

FIG. 6 is a right-side view of an occupancy sensor.

FIG. 7 is a top-side view of an occupancy sensor; and,

FIG. 8 is a bottom-side view of an occupancy sensor.

The broken lines in the drawings illustrate portions of an occupancy sensor that form no part of the claimed design.
